No. 774,592.

PATENTED NOV. 8, 1904.

J. S. MATHEWS.
CURRENT MOTOR OR WATER WHEEL.

APPLICATION FILED MAY 16, 1904.

NO MODEL.

UNITED STATES PATENT OFFICE.

JOHN SMITH MATHEWS, OF PENDLETON, OREGON, ASSIGNOR OF ONE-FOURTH TO W. C. MINNIS, OF PENDLETON, OREGON.

CURRENT-MOTOR OR WATER-WHEEL.

SPECIFICATION forming part of Letters Patent No. 774,592, dated November 8, 1904.

Application filed May 16, 1904. Serial No. 208,282. (No model.)

To all whom it may concern:

Be it known that I, JOHN SMITH MATHEWS, of Pendleton, in the county of Umatilla and State of Oregon, have invented certain new and useful Improvements in Current-Motors or Water-Wheels; and I hereby declare that the following is a full, clear, and exact description thereof, reference being had to the accompanying drawings, which form part of this specification.

This invention is an improvement in water-wheels or current-motors; and its object is to provide a simple and efficient feathering-blade water wheel or motor which can be operated either in a vertical or horizontal position and either wholly or partly submerged, being particularly adapted for generating power for use in irrigating plants, as local power apparatus on farms, and for general power purposes.

The invention consists in the novel construction of the wheel, as hereinafter described and particularly claimed and as illustrated in the accompanying drawings, in which—

Figure 1 is a top view of the wheel, showing it arranged to operate in a vertical position. Fig. 2 is a view showing the wheel arranged to operate in a horizontal position. Fig. 3 is an enlarged detail view of one of the blade-lock hinges.

The wheel comprises a drum A, which may be a regular circle in circumference, but is preferably polygonal, as shown. This drum may be constructed of metal, wood, or any suitable materials and is preferably watertight, particularly when the wheel is to be used in a horizontal position. It is fixedly attached to an axial shaft B, which is journaled in suitable bearings in beams C C, projecting from suitable supports, and a jetty or deflector D is attached to and between beams C C at the return side of the wheel, which will assist in directing the water against the buckets, wings E, or blades on the power side of the wheel and will facilitate the closing of the blades at the return side of the wheel.

Around the periphery of the drum is arranged a series of longitudinal blades, buckets, or wings, which when closed against the drum would cover its periphery, and when the

drum is polygonal I preferably provide a blade for and of sufficient size to cover each facet of the drum. These blades preferably have flanges e on their ends, which flanges may form part of the hinges F of the blades.

The hinge members F are pivoted at f to the ends of hinge lugs or arms G, rigidly fastened to the ends of the drum and projecting slightly beyond the periphery thereof, so that the pivots f are at the periphery of the drum. The hinges F project inwardly beyond the pivots f, these projecting portions forming stop-arms F', which are adapted to move under the fixed hinge-arms G as the blades swing outward until they strike the base portion G' of the fixed hinge-arms, as indicated in the drawings, when they arrest the further outward swinging of the blades and cause the latter to transmit the full force of the current to the drum to rotate the latter. The fixed arms G, it will be observed, form the supporting members of the hinge. They also form stop members of the hinge, and they also form guards to protect the arms F' as they swing thereunder. The flanges e aid in keeping the water-current directly against the blade and give the blades a kind of dish or concave form, which is enlarged by turning the outer edge of the blades slightly inward, as indicated at e' of the drawings.

When the complete wheel is placed in the water, the force of the current at one side of the wheel will swing the blades open and cause the drum to rotate in the direction of the current, while the blades at the opposite side of the drum will swing in and close, so as to offer the least resistance to the current. The resistance is, moreover, lessened by the jetty or deflector, above referred to. Owing to the size of the drum the blades act at some distance from the shaft, and thus gain increased leverage thereon. As the stops of the blade-hinges are located some distance from their pivots, there is less strain on the hinges and less liability of the parts becoming disarranged or damaged by wear than would occur if the lock were at the pivot.

A light spring-band J may encircle the wheel, this band having one end attached to

the jetty and then passing loosely around the wheel back to its point of attachment to the jetty, where it is or may be connected to a rope or chain passed under or over a guide-
5 roller and back to a windlass-drum, which can be operated by lever K or other suitable device. When the band is loose, it will not interfere with the opening of the blades on the power side of the wheel nor the free ac-
10 tion of the wheel; but if the band is tightened it will hold the blades closely to the periph-
15 ery of the drum, and thus throw the wheel out of operation.

When the wheel is in a vertical position, as
15 in Fig. 1, the operative blades are nearest the center of current, where it is most powerful, while the inactive blades are in the more sluggish part of the current, and the jetty insures their closing as they pass toward the
20 current side of the wheel. If the wheel is to be submerged, its ends may be open; but when it is to be only partly submerged, and particularly if used in a horizontal partly-sub-
25 merged position, I prefer to have it air-tight,
30 and in such case it will operate as a floating motor if properly proportioned, the lower blades being the rotative means, while the upper blades will close by gravity as they emerge from the water, and the drum owing
35 to its buoyancy will support the wheel on working position. In cases where the wheel is used in horizontal position the deflector D should be arranged above the axis of the drum and on the upstream or upcurrent side of
40 the wheel, and when the wheel is used in a vertical position the jetty or deflector should also be arranged on the upstream shore side of the wheel.

Power can be transmitted from the shaft
45 of the drum by means of any suitable connections or gearing to the desired point of utilization; but as this transmission means does not form any feature of the present invention it is not shown herein.

Having thus described my invention, what I therefore claim as new, and desire to secure by Letters Patent thereon, is—

1. In a water-wheel, the combination of a hollow drum, an axial shaft therefor, a series
50 of longitudinally-disposed blades having inwardly-bent flanges on their ends, locking hinge-arms rigidly attached to the ends of said blades and projecting over the ends of the drum, fixed hinge-arms attached to the
55 ends of the drum and projecting slightly beyond the periphery thereof, said lock hinge-arms being pivoted to the fixed hinge-arms and projecting inwardly beyond the pivots and stops on the ends of the drum adapted to be engaged by the inner free ends of the locking hinge-arms to lock the blades in open position, all substantially as and for the purpose described.

2. In a water-wheel, the combination of a
65 hollow drum, an axial shaft therefor, a series

of longitudinally-disposed blades, locking hinge-arms attached to the ends of said blades, fixed guard hinge-arms attached to the ends of the drum and projecting slightly beyond the periphery thereof, and pivoted to the lock hinge-arms, said lock hinge-arms projecting inwardly beyond the pivots and adapted to engage the inner ends of the guard hinge-arms, to lock the blade in open position, and a jetty beside the drum adapted to deflect the
70 water toward the drive side of drum, and to close the blades, all substantially as and for the purpose described.

3. In a water-wheel, the combination of a hollow polygonal-sided air-tight drum, an axial shaft therefor, a series of longitudinally-disposed blades, one for each facet of the drum, having inwardly-bent flanges on their ends, locking hinge-arms attached to the ends of said blades, fixed guard hinge-arms attached to the ends of the drum and projecting slightly beyond the periphery thereof, and pivoted to the lock hinge-arms, said lock hinge-arms projecting inwardly beyond the pivots and adapted to engage the inner ends of the guard hinge-arms, to lock the blade in open position, and a jetty beside the drum adapted to deflect the water toward the drive side of drum, and to close the blades, all substantially as and for the purpose described.

4. The combination with the rotary drum, and the blades pivoted thereto; with a blade-closing device encircling the drum and blades thereon, and having its ends attached to non-rotatable points, and means for taking up and relaxing the said device, whereby when the device is relaxed the blades can open, and when tightened the blades are closed against the drum, substantially as described.

5. In combination with the hollow drum, its shaft and bearings; a series of longitudinal blades hinged to the periphery of the drum, and means for arresting the swinging movement of the blades when fully opened; of a non-rotatable band loosely encircling the drum and blades thereon and adapted, when relaxed, to allow the proper opening of the blades, and when tautened to close and hold the blades against the drum, and means for taking up or slackening of the band, substantially as and for the purpose described.

6. In a water-motor wheel, the combination of a drum, an axial shaft attached to said drum, a series of hinge-arms fixedly attached to the ends of the drum; a series of swinging blades extending longitudinally of the drum, said blades having their outer ends bent inwardly and their ends flanged, and extended to form lock hinge-arms on the ends of said blades said arms being pivoted to the outer ends of the fixed hinge-arms, said lock hinge-arms extending inwardly beyond the pivots and adapted to stop the swinging of the blades when fully open, substantially as and for the purpose described.

7. In a water-motor wheel, the combination of a hollow air-drum, polygonal in cross-section, an axial shaft attached to said drum, a jetty beside the drum, a series of hinge-arms 5 fixedly attached to the ends of the drum; a series of swinging blades or wings, one for each facet of the drum, extending longitudinally thereof, said blades having their outer ends bent inwardly and their ends flanged, and 10 lock hinge-arms attached to the ends of said blades, and pivoted to the outer ends of the fixed hinge-arms, said lock hinge-arms extend-

ing inwardly beyond the pivots and adapted to engage the inner ends of the fixed hinge-arms, when the blades are full opened, all substantially as and for the purpose described. 15

In testimony that I claim the foregoing as my own I affix my signature in presence of two witnesses.

JOHN SMITH MATHEWS.
